LIQUID AGITATING AND SIPHON BREAK
APPARATUS

Ernest W. Work, New Britain, Conn., assignor to
The Beaton & Cadwell Manufacturing Company,
New Britain, Conn., a corporation of
Connecticut

Application March 4, 1939, Serial No. 259,877

2 Claims. (CL 261—77)

This invention relates to agitation, and more particularly to an apparatus for introducing a mixture of water and air into the bottom of an open tank for agitating the liquid therein, said apparatus also serving to avoid the possibility of a vacuum occurring in the water supply pipe, and thus prevent back siphonage of liquid from said open tank.

Open wash tanks, such as are used for cleaning electroplated articles or clothes in a laundry, generally have a continuous supply of water fed at the bottom of the tank, the water overflowing at the top thereof. Since the upward flow of the water provides only a small amount of circulation, the water in the tank does not ordinarily become thoroughly agitated. Moreover, in view of possible back siphonage of the contaminated wash water into the supply line in case of a vacuum occurring in the latter, health authorities in many States have prohibited the use of feed pipes disposed at the bottom of wash tanks of this nature.

By means of the present invention, an apparatus has been provided for feeding water into the bottom of a wash tank in which the possibility of liquid being siphoned back into the supply line has been obviated and at the same time the liquid in the wash tank is thoroughly agitated. The apparatus of this invention includes a device adapted to draw air from the atmosphere and mix it with the water being fed to the tank, thus acting simultaneously as an agitator and a siphon break.

The objects of this invention are to provide an improved liquid agitating and siphon breaking apparatus for open tanks which will be relatively inexpensive to manufacture, simple in construction, compact, ornamental in appearance, and very efficient and durable in use.

With these and other objects in view, which will appear as the description proceeds, there has been illustrated in the accompanying drawing one form in which the invention may be conveniently embodied in practice.

In the drawing:

Fig. 1 is a vertical sectional view, on a reduced scale, of an open tank having the invention applied thereto.

Fig. 2 is a vertical sectional view on a larger scale of the Venturi air-aspirating and vacuum breaking device adapted to be installed in the liquid feed line.

Fig. 3 is a bottom view of the Venturi device shown in Fig. 2 looking upwardly.

Fig. 4 is a cross-sectional view of the Venturi

device taken on the line 4—4 of Fig. 2 looking downwardly.

Referring now to the drawing wherein like reference numerals designate like parts throughout the several views, the numeral 10 denotes a tank open at its top and containing a cleaning or wash liquid 11, such as water, which is adapted to be used as a bath for electro-plated articles, or for laundry purposes. Water from a supply line 12 is adapted to be fed through a control valve 13, a short nipple 14, a combined air aspirating and vacuum breaking Venturi device 15, an elongated vertical mixing pipe 16, and a horizontal length of pipe 17 located on the bottom of the tank 10. The pipe 17 is provided with a plurality of spaced apart apertures 18 in its upper surface through which the air and water mixture, which has been thoroughly churned and commingled in the mixing pipe 16, passes upwardly into the tank 10—the end of the pipe 17 being closed by a cap 19. An overflow notch or weir 20 is provided in the upper edge of the tank 10.

The Venturi device 15 is made in the form of a union formed from hexagonal stock, and is internally screw threaded at its upper and lower ends 21 and 22 to receive the lower end of the short nipple 14 and the upper end of the elongated vertical pipe 16, respectively. The Venturi device 15 is provided intermediate its ends 21 and 22 with a restricted passage 23 at the center of the bore 24, said bore comprising a pair of oppositely directed upper and lower flared conical portions 25 and 26, respectively.

An annular groove 27, preferably of V-shaped cross-section, is formed in the outer periphery of the Venturi aspirating device 15 slightly above the level of the restricted passage 23, said groove including a lower inclined surface or annular shoulder 28. A plurality of downwardly extending converging cylindrical air inlet ports 29 lead inwardly from the shoulder 28, and open at their lower ends into the lower flared section 26 of the bore 24 at points just below the restricted passage 23.

Operation

When the apparatus is in operation, the air drawn in by suction through the converging ports 29 due to the passage of the stream of water down through the bore 24 of the Venturi device 15 will be thoroughly commingled with said water and, when it reaches the bottom of the tank, will pass upwardly through the outlet holes 18 in the top of the horizontal pipe 17. The turbulent action of the air and water in the elongated mixing pipe

16 causes the air to be suspended in the water in the form of bubbles 30 which are adapted to rise rapidly through the water 11 in the tank 10, thoroughly agitating it, and resulting in a better cleaning or rinsing of the plated or laundered articles (not shown) contained in the tank 10.

Any sediment or solid particles in the tank will thus be suspended in the liquid and will pass out of the tank through the overflow notch 20, instead of accumulating in the bottom of said tank.

If a vacuum should accidentally occur in the supply line above the device 15, which might have a tendency to cause contaminated liquid 11 from the tank 10 to be sucked back into the supply line, this vacuum will be efficiently destroyed by the air entering the device 15 through the ports 28.

One advantage of the present invention is that it will function as a combined liquid-agitating and vacuum-breaking apparatus.

A further advantage is that owing to the supply of air suspended in the water, the effective volume will be increased, and hence a considerable saving will be made in the amount of water required to accomplish a given amount of washing or cleaning.

In fact, this apparatus has been approved and advocated by the Connecticut State Board of Health, and installations thereof have already been made in various localities in Connecticut.

It will also be understood that the present invention may be applied for aerating purposes, such as aquaria, sewage tanks, or swimming pools within its general principles and scope.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In an apparatus for agitating an aqueous cleaning liquid provided with a tank having an overflow at the top thereof for containing said liquid, and a pipe connected with a water supply line for feeding water to said tank, characterized by having an apertured Venturi aspira-

tor in said pipe above said overflow for drawing air from the atmosphere and commingling it with the water flowing in said feed pipe, and means to deliver the air and water mixture from said feed pipe into said cleaning liquid adjacent the bottom of said tank to thoroughly agitate the liquid and cause solid particles to become suspended therein and be drawn off at said overflow and thus prevent said particles from accumulating in the bottom of said tank, said aspirator preventing the possibility of accidental back-siphonage of the cleaning liquid from said tank to said water supply line, said aspirator comprising a union internally threaded at both ends for connection with adjoining externally threaded sections of said pipe in which it is included, and having a restricted double-conical bore provided with a plurality of upwardly inclined air-inlet passages connected to said bore below said restricted section.

2. In an apparatus for agitating an aqueous cleaning liquid provided with a tank having an overflow at the top thereof for containing said liquid, and a pipe connected with a water supply line for feeding water to said tank, characterized by having an apertured Venturi aspirator in said pipe above said overflow for drawing air from the atmosphere and commingling it with the water flowing in said feed pipe, and means to deliver the air and water mixture from said feed pipe into said cleaning liquid adjacent the bottom of said tank to thoroughly agitate the liquid and cause solid particles to become suspended therein and be drawn off at said overflow and thus prevent said particles from accumulating in the bottom of said tank, said aspirator preventing the possibility of accidental back-siphonage of the cleaning liquid from said tank to said water supply line, said aspirator comprising a union internally threaded at both ends for connection with adjoining externally threaded sections of said pipe in which it is included, and having a restricted double-conical bore provided with a plurality of upwardly inclined air-inlet passages connected to said bore below said restricted section.

3. In an apparatus for agitating an aqueous cleaning liquid provided with a tank having an overflow at the top thereof for containing said liquid, and a pipe connected with a water supply line for feeding water to said tank, characterized by having an apertured Venturi aspirator in said pipe above said overflow for drawing air from the atmosphere and commingling it with the water flowing in said feed pipe, and means to deliver the air and water mixture from said feed pipe into said cleaning liquid adjacent the bottom of said tank to thoroughly agitate the liquid and cause solid particles to become suspended therein and be drawn off at said overflow and thus prevent said particles from accumulating in the bottom of said tank, said aspirator preventing the possibility of accidental back-siphonage of the cleaning liquid from said tank to said water supply line, said aspirator comprising a union internally threaded at both ends for connection with adjoining externally threaded sections of said pipe in which it is included, and having a restricted double-conical bore provided with a plurality of upwardly inclined air-inlet passages connected to said bore below said restricted section.

4. In an apparatus for agitating an aqueous cleaning liquid provided with a tank having an overflow at the top thereof for containing said liquid, and a pipe connected with a water supply line for feeding water to said tank, characterized by having an apertured Venturi aspirator in said pipe above said overflow for drawing air from the atmosphere and commingling it with the water flowing in said feed pipe, and means to deliver the air and water mixture from said feed pipe into said cleaning liquid adjacent the bottom of said tank to thoroughly agitate the liquid and cause solid particles to become suspended therein and be drawn off at said overflow and thus prevent said particles from accumulating in the bottom of said tank, said aspirator preventing the possibility of accidental back-siphonage of the cleaning liquid from said tank to said water supply line, said aspirator comprising a union internally threaded at both ends for connection with adjoining externally threaded sections of said pipe in which it is included, and having a restricted double-conical bore provided with a plurality of upwardly inclined air-inlet passages connected to said bore below said restricted section, said aspirator having an exterior annular groove intermediate its ends, and a plurality of air-inlet passages passing through the wall of said aspirator and having their outer ends opening to the atmosphere in said groove.

ERNEST W. WORK.
